CYCLOTRON TUNING APPARATUS

Winfield W. Salisbury, Cedar Rapids, Iowa, assignor to Collins Radio Company, Cedar Rapids, Iowa, a corporation of Iowa

Application April 12, 1950, Serial No. 155,511

8 Claims. (Cl. 250—27)

1
This invention relates in general to cyclotron oscillators, and in particular to a method of starting the cyclotron to get it past the condition in which the dees are detuned due to electron vibration in the neighborhood of the dees.

Although generally the chamber of a cyclotron is pumped to a substantially low pressure there are always some residual particles left in the chamber and some of these particles become charged. In order to operate a cyclotron, an alternating voltage must be impressed between the dees to accelerate ions. The charged particles initially in the cyclotron chamber have a tendency to detune the dee circuit, and thus make it difficult to bring the dees up to the operating voltage. The reason for the detuning by the charged particles is that if the particle is a free electron it will oscillate between a dee and the wall of the chamber as the initial relatively small voltage is applied to the dees. As the charged particle is accelerated it absorbs energy from the dee, and when it strikes a gas particle or the walls, it gives energy to them. When a large number of these charged particles are oscillating and fail to reach the wall of the cyclotron, or the dee, and give up enough charge to make them neutral, the entire dee system is badly detuned. As soon as the voltage between the dees builds up to a high enough value substantially all of the residual particles will contact either the dees or the walls of the cyclotron and thereby lose their charge. When this condition exists, the charged particles no longer present any interference to the operation of the dees and they oscillate at the true resonant frequency. It is well known that in order to get optimum operating conditions a driving oscillator should be tuned to the driven circuit. The dees form a resonant driven circuit and the driving energy is furnished by the oscillator. Since the dees are initially resonant at some frequency other than the operating resonant frequency, due to the above described phenomena, it is advantageous to be able to detune or change the frequency of the driving oscillator during starting conditions and to change it back to the operating resonant frequency after the voltage has been raised.

It is an object of this invention, therefore, to provide a novel driving oscillator for a cyclotron which is automatically tunable and which will adjust itself to overcome the initial detuning caused by the residual charged particles in the cyclotron chamber.

Another object of this invention is to provide means whereby the driving oscillator of the cyclo-

2
tron may be automatically tuned to a frequency which will drive the dees above a critical voltage so that the detuning effect caused by the residual charged particles may be overcome and which will then change the frequency of the driving oscillator to a frequency near the resonant frequency of the dee system.

Yet another object of this invention is to provide means for preventing the oscillator tubes of a cyclotron from drawing excessive grid current.

A feature of this invention is found in the provision for a tunable element comprising an inherent inductance and capacitance which may be connected in the oscillating circuit of a driving oscillator for varying the frequency.

Further objects, features, and advantages of this invention will become apparent from the following description and claims when read in view of the drawings; in which

10 Figure 1 is a schematic illustration of the dees of the cyclotron with a driving oscillator connected thereto and an oscillator tuning element connected for automatically tuning the oscillator to the desired frequencies;

15 Figure 2 is a detailed isometric view of the oscillator tuning device of this invention;

Figure 3 is a schematic illustration of a modification of the invention; and

20 Figure 4 is a schematic of another modification.

25 Referring to Figure 1, a pair of cyclotron dees 10 and 11 are shown with their stems 8 and 9 connected to the shorting bar 12 which is of copper or other suitable material. It is to be understood that the dees form part of a conventional cyclotron of the type well known to those skilled in the art, wherein the dees are held in a predetermined spatial relationship between a pair of pole pieces of a direct current

30 magnet which passes an exciting field at right angles past the dees. The operation of the cyclotron is well known and requires the introduction between the dees of charged particles. They are accelerated spirally due to the action of the magnetic field from the pole pieces and an electric alternating field which is impressed between the dees. This alternating current field is impressed across the dees by connecting an oscillator, designated generally as 13, to them. The oscillator

35 13 comprises the tubes 14 and 16, respectively, which have their plates 17 and 18 connected together by the inductive coupling loop 19. The inductive coupling loop 19 extends down closely adjacent to the stems 8 and 9 to drive them.

40 **45** Between the mid-point 21 of the coupling loop

19 and a shorting bar 12 is connected an inductance 22. The shorting bar may be grounded. The coupling loop 19 is placed adjacent the shorting bar 12 and the voltage induced in the dees is greatly increased and amplified at points further away from the shorting bar and the coupling loop. For example, the maximum amplitude of the voltage on the dees 10 and 11 will occur adjacent their accelerating ends and will be zero at the shorting bar because it comprises a direct short. The cathodes 23 and 24 of the tubes 14 and 16 are tied together and are connected to B-. Between the grids 26 and 27 of the tubes 14 and 16, respectively, is connected a tunable circuit which comprises the interelectrode capacitances C_{14pg} and C_{16pg} and the variable inductance-capacitance 28. C_{14pg} is the plate to grid capacitance of tube 14 and C_{16pg} is the plate to grid capacitance of tube 16. A grid leak resistor 29 connects the mid-point of a coil 31 in the inductance-capacitance 28 to the cathodes 23 and 24.

The inductance-capacitance is better shown in Figure 2 and comprises the housing member 32 which supports the coil 31. The coil 31 enters the housing 32 through one end thereof and emerges from the opposite end. Transversely pivoted in the housing 32 are a plurality of shafts 33 which extend transversely through the coil 31. Carried intermediate the ends of each shaft 33 is a disc of substantially circular shape 34, which may be of copper or other suitable material. The shafts 33 are connected together by the belts 36 which are attached to pulleys 37 so that if any one of them is moved, the others turn correspondingly. The discs 34 are smaller in diameter than the internal diameter of the coil 31 and thus may be freely rotated within the coil. A bracket 38 is connected to the housing 32 and pivotally supports therein a shaft 39 which has attached thereto the pulley 41. A belt 42 connects the pulley 41 with one of the pulleys 37 so that the shafts 33 may be rotated in response to the movement of shaft 39. When the discs 34 are aligned so that their plane is parallel to the longitudinal axis of the coil, maximum inductance may be obtained from the coil. On the other hand, when the shafts 33 are rotated until they are transverse to the coil 31, the inductance is at a minimum because the copper discs 34 tend to short out the lines of flux between adjacent coils and thus substantially decrease the inductance.

A starting switch 25 starts operation of the cyclotron and closes the oscillator circuits. The discs 34 are initially adjusted relative to the coil 31 so that a large inductance is obtained. When the starting switch 25 is engaged it actuates a timer 20. After a preset time the timer closes the circuit to a drive motor 39. The motor 39 is connected to the shaft 39 through the mechanical linkage 45 and thus the discs are rotated to decrease the inductance in coil 31 and to tune the oscillator to the dees.

The shaft 39 may be rotated manually from a shielded room adjacent the cyclotron if desired.

A voltage probe may be attached to the dees to indicate when the change in inductance should occur. It may be connected to a motor control circuit, not shown, which actuates the motor.

Figure 3 illustrates a modification of this invention wherein a relay 45 has been connected in series with a resistor 29. The armature 46 of the relay is mechanically linked to a crank arm 47 which is connected to the shaft 39 of the inductor-capacitor inductance 28. The timer 20 and motor 39 illustrated in Figure 1 have been eliminated.

In operation the apparatus of Figure 3 is initially set to the starting position with the discs 34 set to their maximum inductance position. When the oscillations are initiated, the grid current becomes larger and larger until finally the current through the resistor 29 and the relay 45 is such as to move the armature 46, thus changing the position of the discs 34. This returns the oscillator circuit to the desired operating point. The armature 46 of the relay 45 will continue to be held in the closed position even though the discs 34 have been moved to decrease the inductance for the reason that once the armature has closed, less current is required to maintain it in a closed position than is necessary to cause the closing of the relay.

Figure 4 illustrates a further modification of the invention wherein inductance capacitance 28 has been eliminated and an inductive loop 48 has been substituted therein. A loop 48 provides the inductance necessary for operation of the oscillator and with the inner electrode capacitances C_{14pg} , and C_{16pg} comprises the oscillator's tuned circuit. A relay 49 has its winding 51 connected in series with the loop 48 and has a movable armature 52 which is mechanically linked to a shorting bar 53. When the cyclotron is started, the armature 52 is open and the grid current flows through the inductive loop 48. When the current in the loop 48 reaches a predetermined value the armature 52 of the relay 49 closes, thus shorting a portion of the loop 48. This results in a decrease in inductance which in turn causes a reduction in grid current. This prevents overloading of the grids of the tubes 14 and 16.

It is seen, therefore, that this invention provides means for starting the cyclotron and driving it to a condition where the original detuning, due to the residual charged particles, will be overcome and without subjecting the grid circuit to overload for a long period.

Although this invention has been described with respect to particular embodiments thereof, it is not to be so limited as changes and modifications may be made therein which are within the full intended scope as defined by the appended claims.

I claim:

1. In a cyclotron having dees which are initially detuned due to residual charged particles within the dee chamber and in which the dees are excited by a driving oscillator, oscillator tuning means comprising an inductance coil connected between the grids of the oscillator tubes, support means connected to the coil, a shaft pivotally supported in said support means transversely of said coil, a generally flat non-magnetic member connected to said shaft within the confines of said coil, driving means connected to said shaft for rotating it relative to said support member, control means connected to said driving means to actuate it so that the inductance of said coil may be changed to tune the driving oscillator to the dees, and a timer connected to said control means to energize it.

2. In a cyclotron having a pair of dees and a driving oscillator, means for tuning said oscillator comprising, an inductance coil in the resonant circuit of said oscillator, a paddle supported for rotary motion relative to said coil, and with said paddle having a substantial area within said coil and rotatable about an axis transverse to said coil, driving means connected to said paddle to tune the driving oscillator to the cyclotron dees.

3. Starting means for a cyclotron having a pair of dees and a driving oscillator comprising, a frequency control circuit for said oscillator, in-

ductive means connected to the frequency control circuit, means for changing the inductance of said inductance means, and cyclotron starting means connected to said means for changing inductance to actuate it during the starting period.

4. In a cyclotron having dees which are initially detuned due to residual charged particles within the dee chamber, and in which the dees are excited by a driving oscillator, automatic tuning means comprising, a frame member, an inductance coil supported in said frame member with said coil being connected in the resonant circuit of the cyclotron oscillator, a plurality of shafts passing transversely through said frame, a disc member carried on each of said shafts and maintained within the confines of said coil, driving means connected to said shafts, timing means controlling said driving means, and said timer actuated by the starting switch of the cyclotron to vary the inductance of said coil to keep the oscillator tuned to the dees during the starting cycle.

5. Starting means for a cyclotron having dees which are initially detuned due to the residual charged particles in the dee chamber and in which the dees are excited by the driving oscillator, automatic tuning means comprising a bracket member, a coil supported in said bracket, and with said coil connected in the resonant circuit of said oscillator, a plurality of transverse shafts pivotally supported in said frame and passing transversely through said coil, a disc member carried on each shaft within the confines of said coil, flexible means interconnecting said shafts so that when one is rotated they all will rotate, driving means connected to one of said shafts, a timer connected to said driving means to actuate the inductance change, and the starting switch for said cyclotron connected to said timer so that the timer will actuate the motor to maintain the oscillator tuned to the dee system of the cyclotron.

6. In a particle accelerator having electrodes which are initially de-tuned, and in which the dees are excited by a driving oscillator, auto- 45

matic tuning means comprising, variable inductance means, a relay circuit connected in the grid circuit of the driving oscillator, and an armature of said relay connected to said variable inductance means to vary it in response to energization of said relay.

7. In a particle accelerator having electrodes which are initially de-tuned and in which the dees are excited by a driving oscillator, automatic tuning means comprising an inductive loop connected in series between the grids of the oscillator tubes, an electromagnetic means connected in series with said loop, a shorting bar movable to a first position disengaged with the loop and movable to a second position in engagement with the loop, mechanical linkage between the bar and said electromagnetic means to move the shorting bar from the first to the second position in response to actuation of said electromagnetic means.

8. Means for automatically tuning the driving oscillator of a cyclotron having an inductive loop between the grids of the oscillator tubes comprising, a shorting bar movable into and out of engagement with said loop, a relay connected in series with said loop, a movable armature connected to said relay, and mechanical linkage connecting said shorting bar to said armature to move it from a first position out of engagement with said loop to a second position into engagement with said loop.
